Apollos Richmond of Providence, R.I.

Assignor to

A. G. Barstow of same place

Letters Patent No 473 Dated July 13th 1852

uuuuuu

The schedule referred to in these Letters Patent and making part of the same

To all persons to whom these presents shall come:

Be it known that I, Apollo Richmond of Providence in the County of Providence and State of Rhode Island have produced a new and original design for a portable grate, and I hereby declare that the said new design is fully described and represented in the following specification and accompanying drawings, which reference is herein after made.

The figures of the accompanying plates of drawings represent my new design. In Plate 1 Fig 1 is a front elevation of the grate and fig 2 is a section of the same taken in the plane of the line AB. In Plate 2, fig 3 is a plan or top view of the same.

The front plate of the grate is ornamented with gothic arches a, a, & c, pendants b, b, b, and raised gothic mouldings c, c, enclosing pendants b, b. The sides of the front plate are curved as shown in fig 1, pl. 1, and are ornamented with the raised figures d, d, d, d. From these curved sides project the ornamented corbel or bracket projections e-e with the raised figure f, f and gothic stars g, g.

The blower is ornamented with arches a, a, a, and raised mouldings c, c. The upper portion h, h, of the grate has on it the raised semi-circular mouldings i, i and elongated figure k, k.

The bottom plate has around it the mouldings l, l, l, and the vine and flower work m, m. The top plate has around it the mouldings n, n, n, n, and the flower work m, m. The cover is ornamented with the raised points p, p and flower work m, m.

Having thus described my new design I shall state my claim as follows:-

What I claim as my production and desire to have secured to me by Letters Patent is the new design consisting of the gothic arches, mouldings, pendants &c. herein above described & represented in the drawings for a portable grate.
